UNITED STATES PATENT OFFICE.

EMRECH KAVECANSKY, OF CLEVELAND, OHIO.

CLOTHES-MANGLE.

1,251,384.

Specification of Letters Patent.

Patented Dec. 25, 1917.

Application filed June 28, 1917. Serial No. 177,497.

To all whom it may concern:

Be it known that I, EMRECH KAVECANSKY, a subject of the King of Hungary, residing at Cleveland, in the county of Cuyahoga and 5 State of Ohio, have invented certain new and useful Improvements in Clothes-Mangles, of which the following is a specification.

This invention relates to new and useful 10 improvements in clothes mangles.

An object of the device is to provide a mangle having pairs of smoothing rolls arranged with individual tensioning means while a master tensioning means is arranged 15 for simultaneously tensioning the rolls in a uniform manner.

In the drawing forming a part of this application, and in which like designating characters refer to corresponding parts 20 throughout the several views:

Figure 1, is an end elevation of the device,

Fig. 2 is a side view of a portion thereof partially broken away.

Fig. 3 is a vertical sectional view taken 25 upon line III—III of Fig. 2,

Fig. 4 is an enlarged detail vertical sectional view showing the position of the feeding arrangement for the rolls.

Referring more in detail to the drawing 30 a base plate 10 is arranged having opposite end walls 11 in which the lower rolls 12 and 13 of vertical pairs of mangle rolls are journaled, gears 14 and 15 being arranged upon adjacent ends of the said rolls 12 and 35 13 respectively. An idler pinion 16 is mounted on a stub shaft 17 carried by the wall 11 and is in constant mesh with the gears 14 and 15 while a relatively larger power gear 18 in mesh with the pinion 16 40 is secured to a shaft 19 journaled through the walls 11 and is provided with a turn wheel 20 upon its opposite end having a crank handle 21.

Pressure rolls 12' and 13' are provided 45 above and for coöperation with the aforementioned rolls 12 and 13 respectively, the pressure rolls being journaled in blocks 22 slidably arranged in vertical slots 23 in the end walls 11. Upright screws 24 are carried by the blocks 22 having follower strips 25 slidably mounted upon the said screws in parallel relations above the rolls 12' and 13' while the springs 26 encircle the screws 24 and are arranged between the blocks 22 and 50 the strip 25. Adjusting nuts 27 are threaded upon the upper ends of the screws 24

whereby the springs 26 may be separately tensioned with respect to the ends of the pressure rolls.

The strips 25 are formed of resilient material such as wood and are connected together centrally by a yoke 28 the same having a screw 29 freely extending centrally through the same with its lower end secured to a longitudinal beam 30 arranged between 60 the end walls 11 adjacent the tops thereof. A spring 31 is arranged between the yoke 28 and the beam 30 while a regulating nut 32 is threaded upon the screw 29 and whereby as will be evident, a turning of the nut 32 70 will forcibly lower the yoke 28, depressing the spring 31 as well as the strips 25 and exerting an even pressure upon the spring 26 for resiliently maintaining the pressure rollers 12' and 13' in desired relations with 75 respect to the bottom rolls 12 and 13.

A swinging table 33 is pivoted between the ends 11 at the inlet side of the device the same being provided with a leg 34 for normally resting upon the base 10 when the 80 table is operatively positioned, said table being capable of swinging upwardly and inwardly when not in use as shown by dotted lines in Fig. 3. Similarly, a swinging leaf 35 is provided at the outlet side of the device 85 for receiving the outgoing goods, this leaf being inwardly foldable when not in use as also shown by dotted lines in Fig. 3. An apron 36 is arranged over the lower roll 13 and also over a rod 37 journaled between the 90 end walls 11 the arrangement being such that the goods to be operated upon such as the fabric 38 shown in Fig. 4 will be fed to the pair of rolls 12, 12' in a plane slightly above the space therebetween. By means of 95 this arrangement the fabric is grasped by the rolls in a smooth condition and without being permitted to wrinkle or overlap as sometimes occurs when the horizontal portion of the feeding apron lies in or below the plane of the top of the lower receiving roll. The operation of the device will be apparent from this detailed description thereof, it being noted that upon turning the wheel 20 by means of the handle 21 the 100 lower rollers 12 and 13 are revolved in the same direction, carrying the horizontal portion of the apron 36 away from the table 33 and toward the leaf 35 so that the introduction of the fabric 38 upon the apron 36 at a 105 point adjacent the table 33 presses the fabric between the roll 13' and the apron 36 and

feeds the same through the device to the rolls 12, 12' where the same is smoothed and pressed and passes outwardly through the machine upon the leaf 35.

- 5 A serviceable device is provided in which any articles may be pressed and smoothed without wrinkling or folding, such as damp fabrics or sheetings, giving the effect of a partial ironing and assisting in preparing 10 the goods for use. The gist of the invention resides in the resilient tensioning means for the pressure rolls.

What I claim as new is:—

1. A clothes-mangle, including spaced 15 apart pairs of smoothing rollers, those of each pair being superposed one with relation to the other, the upper rollers of the pairs having their shaft-bearings vertically movable, said bearings having upwardly extend- 20 ed screw-threaded and nut-equipped stems, springs applied to said stems and adapted to exert pressure upon said roller-shaft bearings, follower-strips applied to said stems

and bearing upon said springs, a yoke se- 25 cured to the follower-strips about centrally thereof, and means for applying pressure through said yoke to said follower-strips.

2. A clothes-mangle including spaced- apart pairs of smoothing rollers, those of each pair being superposed one with relation 30 to the other, the upper rollers of the pairs having their shaft bearings vertically mov- able, said bearings having upwardly extend- ed screw-threaded and nut-equipped stems, 35 springs applied to said stems and adapted to exert pressure upon said roller-shaft bear- ings, follower-strips applied to said stems and bearing upon said springs, a yoke se- cured to the follower-strips about centrally 40 thereof, a second stem having one end fixed and extending freely through said yoke and having applied thereto a spring intermediate said yoke and the point of fixture of said stem.

In testimony whereof I affix my signature. 45

EMRECH KAVECANSKY.
